(57) **CLAIM**

I claim the ornamental design for a hand held back and body scrubber, as shown and described.

DESCRIPTION

FIG. 1 is a front perspective view of the hand held back and body scrubber.

FIG. 2 is an enlarged back perspective view of the hand portion of the hand held back and body scrubber.

FIG. 3 is an enlarged perspective view of the handle portion of the hand held back and body scrubber; and,

FIG. 4 is a perspective view of the side of the hand held back and body scrubber.

The broken line shown just inside the perimeter of the hand component is stitching, and is part of the claimed design. The remaining features shown in broken lines illustrate portions of the article of manufacture that form no part of the claimed design.

The claimed design is characterized by a hand-shaped scrubbing cover mounted on a removable handle with a loop. The hand-shaped scrubbing cover and the handle combine to form the unitary design of the hand held back and body scrubber.
